DEFECATOR

William C. Groeniger, Columbus, Ohio, assignor
to John B. Pierce Foundation, New York, N. Y.,
a corporation of New York

Application June 30, 1934, Serial No. 733,259

16 Claims.

(Cl. 4—69)

My present invention relates to defecators particularly of the lateral outlet type.

The invention is applicable to defecators inclusive of water closet bowls, urinals, and hospital 5 and other sinks, dental, medical and other sanitary bowls, and other receptacles, advantageously having an outlet at a lateral side, and provided with suitable means for the supply of water or equivalent effluent, affording under sanitary conditions a mass of fluid for the well portion of the 10 defecator, serving to receive solid and/or semi-solid and/or fluid matter to be evacuated, and for the further purpose of flushing the defecator to discharge such flowable mass into a soil pipe or 15 equivalent, the stated parts being coordinated to effect the respective operations under the condition of substantial absence of sound.

Embodiments of my invention may be generally classed as of the type frequently referred 20 to as the wall-hung type, but such nomenclature as may be applied to my invention is indicative merely of the adaptability of embodiments of my invention to be positioned at or approximate a wall, since, as appears more fully hereinafter, 25 defecators embodying my invention may be positioned at any location independently of the location of a wall and may be suitably supported other than by or in proximity to a wall.

Marked advantages are possessed by embodiments of my invention by reason of the operation 30 of the discharge by water and air pressures and water and air momentums effective conjointly during the discharge stage. By reason of such coordination of water and air pressures and of 35 water and air momentums the amount of water required to effectuate the discharge is reduced to a minimum. Furthermore, defecators embodying my invention may be operated at minimum pressure of water or other supplied effluent.

Such coordination of pressures and momentums respectively exercised by the air and the effluent bestows upon embodiments of my invention 40 the optimum quality of silence in operation.

Essential characteristics of preferred forms of 45 my invention reside in imparting by the supplied effluent to the after-fill a vortex movement and conjointly therewith an upflow movement through the trapway to effect the discharge of the contents of the bowl. Such vortex movement creates a 50 momentum of the fluid mass within the well of the bowl, a component of the force of such momentum assisting the force of the upflow movement through the trapway, attended by the lowering of the central area of the fluid mass within 55 the well and resulting force exercised by the

downwardly directed current of air, such central lowering of the fluid mass effecting positive force upon matter contained in and including all floating matter toward and through the intake and upwardly of the trapway.

Further features and objects of the invention will be more fully understood from the following detail description and the accompanying drawings, in which

Fig. 1 is a top plan view of a preferred form of 10 my invention.

Fig. 2 is a vertical central sectional elevation of Fig. 1.

Fig. 3 is a vertical elevation of Fig. 1 as viewed 15 at its rear side.

Fig. 4 is a detail elevation on the arcuate section line 4—4 of Fig. 2.

Fig. 5 is a detail sectional view on line 5—5 of Fig. 2.

Referring to the drawings, the bowl 10 and the 20 coordinated parts are representative of any suitable form of defecator adapted to my invention.

The bowl 10 is shown comprising generically an upper portion 11 and a lower or well portion 12. The normal level of the mass of water 13 or 25 other matter-receiving and effluent fluid, known as the after-fill, is indicated at 14. Such mass of fluid serves as the trap sealing fluid.

Suitable provision of means are incorporated 30 in the bowl affording an initial mass of water or other effluent serving as the after-fill for receiving any solid and/or semi-solid and/or fluid matter, and further providing upon the supply of the effluent to effect the discharge of such flowable mass, such provision of means being embodied 35 in the appurtenant parts of the bowl to be wholly operative at minimum pressure and minimum quantity of the supplied effluent, and utilizing the momentum of the effluent conjointly with engendered currents of air to impart silence during 40 the period of discharge.

Such provision of means includes a trapway or upflow leg indicated at 15 and a dam or weir 45 16 effective to seal a portion of the mass of the effluent in the trapway 15.

Such up-flow leg 15 is afforded by the inwardly disposed ledge 18 extending downwardly toward the well portion 12 of the bowl, its terminal portion 18a being disposed in predetermined relation vertically and horizontally with respect to the 50 central area of the well portion 12, as appears more fully hereinafter. The upper rearward portion of the up-leg 15 is defined by the septum 19 terminating in the wall formation of the discharge opening 20, for the reception and secure- 55

ment therein of a suitable evacuator 21. Any suitable type of connection between the receiving end 21a of the evacuator 21 and the wall formation 20 of the discharge opening of the up-flow leg 15, may be employed.

- The stated ledge 18 extends upwardly as indicated at 18b to serve as a septum to define one side of the main water channel 22, the inflow port 23 of which may have any suitable wall formation adapted for a connection with any suitable supply of water or other effluent, such as a gravity water tank or a nipple provided with a flush valve, for supplying water from a domestic or local pressure water line, pressure tank, etc.
- Such main water channel 22 is defined at its lower portion by the stated septum 19. The upper or top wall 24 of the main water channel may be afforded by the rearward horizontal ledge or shelf of the bowl.
- The effective contour of the up-flow leg 15 may be of substantially uniform circular cross-section, as shown; such cross-section may vary in relative cross-section from its intake to its outflow, as is set forth in my co-pending application, Serial No. 749,069, filed Oct. 19, 1934, entitled Defecators.

The bowl proper may be supported in the indicated substantially horizontal position in any suitable manner. Advantageously, the bowl is supported by attachment to a wall indicated by the line 25, the material of the bowl proper being extended for such form of support, viz., by a rearward vertical web 26 extending to a vertical back plate 27, which extends substantially parallel to the face of the wall 25 and substantially normal to the web 26.

The upper bowl portion 11 is preferably of multi-conical formation, as shown; however, certain essentials of my invention are not limited to the illustrated form.

Preferably, the uppermost portion 11a inclusive of the web 18b is inwardly concave, receding from the vertical plane with respect to the effective area of discharge of the rim openings 28 provided for in the rim formation 29, the effectiveness of such relationship being set forth hereinafter. The rim formation 29 includes the rim channel 30 which extends about the top of the bowl and has an intake port 31 communicating with the main water channel 22.

An essential feature of each rim opening 28, in its preferred formation, includes the outwardly divergent effective discharge in a direction toward the outer face of the bowl with respect to the vertical, whereby any matter possibly deposited on the inner face of the wall, particularly the back wall 18b of the upper wall portion 11a of the bowl, is subjected to a quasi-chiselling action by the jet of water discharged through the rim opening. Such preferred form of rim jet discharge may be employed for the forwardly disposed rim openings 28, and/or at the sides of the bowl.

The rim openings, particularly the sets thereof disposed about the sides of the bowl, further, are directed to cooperate with the vortex jet of the main discharge flow means of the bowl, later described, to initiate and/or enhance such vortex movement of the flowable mass 13.

The stated provision of means for positively eliminating noise during the stage of discharge of the bowl comprises channel means, shown in the form of two oppositely disposed channels 32 respectively having intakes 32a communicating with the main water channel 22 and outflow ports 32b, the latter communicating with the up-

flow trap leg 15. Advantageously, such channels or ports 32 are formed in the septum 19 and side walls of the up-flow leg 15, thus locating the out-flow ports 32b to be directed upwardly relative to the effluent 13 disposed initially dormant 5 within the up-flow leg 15.

Such channel means 32 serve also for the flow of the effluent to and through the vortex jet 33, which may terminate in a nozzle formation, the same being directed, as appears in Figs. 1 and 2, to maintain a vertical movement of the mass of the fluid 13 within the bowl, say, in a counter-clockwise direction.

It will be observed that the out-flow port or ports 32b and the vortex opening 33 are located 15 within the mass 13 of the effluent, that is to say, below the normal level 14 of the same; the extent of submersion and the area and arrangement of opening of the channel out-flow port or ports are determined by the desired degree of up-flow effect 20 to be imparted to the portion of the flowable mass 13 within the trapway 15. The extent of submersion and the area and arrangement of opening of the vortex jet 33 are determined by the 25 desired degree of vertical movement to be imparted to the portion of the mass 13 within the lower portion of the bowl 10.

Preferably, as shown in the drawings, each out-flow port 32b extends at opposing side walls 15a, 15a, see Fig. 5, of the upflow leg 15 and opens out over an elongated area, its mean direction of opening being substantially in alignment with the mean upward direction of the upflow leg 15.

The bowl and the stated component parts may be of vitreous material suitably molded and otherwise treated, or of cast metal or other proper material, enamelled or otherwise appropriately surfaced and/or suitably treated. The defecator illustrated in the drawings, and to scaled dimensions, has been designed for manufacture of porcelain, suitable provision being made for the proper coring of the channel parts, allowance for shrinkage of the material ensuing during the baking stage, etc. The stated preferred form of the rim openings is conveniently had by drilling through the uppermost wall of the rim 29 during an intermediate baking stage, the thus formed drill openings in the upper wall of the rim 29 being later plugged with the porcelain-forming material to eradicate the same in the final status 50 of the bowl.

Coordinated with such up-flow discharge means 32 I provide an evacuator 21, set forth more particularly and claimed per se in my co-pending application Serial No. 4,620, filed Feb. 2, 1935, entitled Evacuators, now U. S. Patent #2,055,490, granted September 29th, 1936.

For the purposes of the present invention, such evacuator 21 in construction and function possesses the following essentials: an upper section 21b, conveniently also forming the upper elbow section of the evacuator, a relatively cross-sectionally restricted downwardly extending section 21c, and a lowerly effluent curtain forming section 21d. The outtake section 21e is adapted to be connected in any suitable manner to a Y-fitting or other laterally opening fitting leading to a soil pipe, waste pipe, etc.

The evacuator, as above described and as shown 70 in Figs. 1 and 2 of the drawings, has a resulting general Z-formation. The lower elbow formation 21d and therewith its outflow chamber 21e may be angularly related to the stated upper sections of the evacuator as desired, viz., at a 45° 75

angle as appears from Fig. 1, or at a 90° angle, or at a zero or any intermediate angle, depending upon the relative location of the Y- or other fitting and/or the soil pipe or waste pipe with which the evacuator is connected.

The general operation of defecators embodying my invention, will be largely apparent from the preceding. By reason of the provision of the flow of water from the main chamber 22 into and through the channels 32 inclusive of the vortex opening 33, up-flow movement of the flowable mass within the up-leg 15 is initiated at minimum pressure and with minimum volume of the effluent. The vertical movement effected by the jet discharged through the vortex opening 33 is conjoint in its action with the jets directed through the ports 32b, in effecting an up-flow movement of the flowable mass through the trapway 15, thus utilizing the co-timed forces of the pressure and volume of water supplied as the effluent and those engendered by the currents of air, coupled with the momentum of the flowable mass created by the stated vortex movement and the stated up-flow movement.

In the operation of the practical embodiments of my invention, such conjoint action takes place without substantial rise of the mean level of the flowable mass within the well portion of the bowl; the displacement of the flowable mass by the up-flow jets emerging through the ports 32b co-acting with the vortex movement effects in actual operation definite lowering of the level of the central portion of the flowable mass within the bowl, and consequent current of air directed over the flowable mass within the bowl downwardly toward the intake of the up-flow leg.

Such displacement upwardly through the up-flow leg 15 causes the flowable mass to pass over the dam 16 and weir 21f of the evacuator. The preferred formation of the evacuator as is set forth in my aforesaid co-pending application, embodies a weir portion at 21f which is substantially flat, thus providing a curtain of the flowable mass from and downwardly of the weir, the flowable mass then entering the relatively reduced section 21c of the evacuator. Such restriction of the area of the flow brings about the relative rise of the flowable mass above the dam and above the weir 21f, thus creating a quantity of the flowable mass within the upper or elbow section 21b for effectually sustaining siphonic action through the evacuator. Such rise of the flowable mass also causes entrainment of air originally in the bulged or elbow formation of the upper section 21b, a portion of the air remaining there-in during the transit of the siphonic discharge. Access of air through the discharge opening 21e of the evacuator during the siphonic action is positively precluded by the curtain of the flowable mass arising from the flow of the flowable mass through the downwardly extending intermediate section 21c toward the lower elbow or pool section 21d, the level of the pool serving to co-act by restricting the effective extent of opening through the lower elbow, and further by splashings of the effluent mass against the curved wall formation of such section 21d.

The stated curtain over the weir 21f and within the lower or elbow section 21d are maintained over a time period extending beyond the instant when the level of the central portion of the flowable mass within the well reaches or is below the edge 18a of the ledge 18, that is to say, when air enters the up-leg 15 and passes to and with-

in the upper or elbow section 21b of the evacuator, and thereupon "breaking" the siphonic action. The inflow of such "breaking" air is enhanced by the air under sub-atmospheric pressure within the upper elbow section during 5 the stage of siphonic passage.

The jets discharged through the rim openings 28 serve the conjoint purposes of scouring the sides of the bowl above the level of the flowable mass, and to enhance the vertical movement of 10 the flowable mass within the bowl. Upon the cessation of the siphonic action, the water above the dam 16 returns through the trapway 15 into the well, to serve partly as the after-fill; the remainder of the after-fill and trap sealing fluid 15 is furnished by water through the channel means 32, which operation is noiseless as compared with the supply of the after-fill falling from the rim openings.

The above stated jet formations and consequent displacement and movements of the flowable mass, inclusive of those of the water or other effluent, are thus positively provided for without attendant noise. Further, the flow of the flowable mass inclusive of the continued supply of the water or other effluent is had in the absence of noise. Toward the close of the stage 25 of siphonic passage of the flowable mass, by reason of the stated vertical movement and consequent lowering of its central area, air is entrained to more or less extent with the effluent up-flow through the trapway 15, thus gradually increasing the pressure of the sub-atmospheric pressure air above the dam 16, thus precluding 30 the usual "gurgling" sound necessarily inherent 35 in the construction and operation of prior art devices of this character.

It will be noted that the rim openings 28 extend downwardly, thus providing for complete self-draining of these openings. Such arrangement also positively avoids the entrapping of air in the rim channel and/or the rim openings, with resulting operation of the same devoid of noise or other sound.

It is preferable, as is shown in Fig. 2, to locate 45 the central area 12a of the well 12 of the bowl to be disposed substantially vertically below the lower edge 18a of the ledge 18, which provision of means functions to locate solids and the heavier semi-solids within or substantially within the 50 intake orifice of the up-flow leg 15 in advance of the flushing stage of the defecator.

As appears from the disclosure herein, the faces of the interior of the bowl above the well proper of the bowl are substantially smooth and 55 of general conical contour solely increasing in effective radius upwardly without increase of the rate of increase of the radius, to thereby avoid re-entrant or other vertical-movement-retarding wall formation.

The floating and the lighter semi-solid matter received within the flowable mass 13 are positively directed to the center of the mass by the vertical movement of the same engendered by the vortex jet 33 and aided by the rim jets 28, 65 such vertical movement effecting a "lowering" of the level of the central portion of the mass 13 within the bowl proper, whereby such floating and lighter semi-solid matter are positively displaced in a radially inward, downward direction toward the intake orifice of the up-flow leg 15.

It will be observed that the port or ports 32a of the channel means leading to the vortex jet opening and to the trapway upflow jet commu- 75

nicate with the main chamber 22 at a location below that of the port 31 leading to the rim openings, thus insuring initiation of the vortical movement and of the upflow movement through the trapway at the beginning of the flushing period.

Preferably as shown in the illustrated embodiment the port or ports 32a are located at the lowermost level of the main chamber 22 to implement maximum force expressed in vortical and/or upflow movement in the use of any given quantity of water supplied to the main chamber, and further to insure positive drainage of the main chamber, the channel means 32, and the jet openings 33 and 32b to prevent breakage due to freezing.

Preferably, the evacuator or other discharge means of the bowl is connected to the out-take of the up-flow leg or trapway, independently of the support of the bowl proper relative to a wall, supporting chair or the like, such as is set forth in my co-pending application, Serial No. 48,860, filed November 8th, 1935, entitled Plumbing connection.

25 As is illustrated in detail in the drawings, the ports 32b are located toward the entrance of the upflow leg 15, laterally opposite to one another and symmetrically positioned relative to the mean longitudinal axis of the upflow leg 15; further, as appears more prominently in Figs. 1 and 4, planes passing vertically through the axes of the respective ports 32b lie at an angle to one another and intersect one another at a location proximate the dam 16, whereby the effluent ejected through the ports 32b combine with one another effectively in the movement of discharge of the contents of the well portion of the bowl into and upwardly of the upflow leg 15 and over the dam 16.

40 Commercially produced embodiments of my invention operate efficiently with a supply of water at the low head of six inches and at the low flow volume of four gallons, delivered, for example, from a regulation open flush tank; such embodiments of my invention operate also highly satisfactorily at three pounds pressure and correspondingly reduced rate of flow of water furnished by a suitable supply under control of a regulation pressure valve.

50 Whereas I have described my invention by reference to specific forms thereof, it will be understood that many changes and modifications may be made without departing from the spirit of the invention.

55 I claim.

1. A defecator comprising in combination a bowl having a portion thereof formed as the unobstructed upflow leg of a trapway, said bowl having a portion thereof formed as a well communicating with the intake of the trapway, the faces of the interior of the bowl above its stated well portion being substantially smooth and of general conical contour solely increasing in effective radius upwardly without increase of the rate of increase of the radius, to thereby avoid re-entrant wall formation, means forming a jet opening communicating with the bowl below the normal fluid level of the trap sealing fluid for imparting vortical movement to substantially the whole of the fluid contained in the bowl, channel means having an outlet communicating with and directed upwardly of and in substantially parallel relation to the direction of flow through the trapway, and means for supplying an effluent to said jet forming means and to said channel

means, whereby the contents of the bowl is discharged without rise of the mean level of the fluid in the bowl.

2. A defecator comprising in combination a bowl having a portion thereof formed as the unobstructed upflow leg of a trapway, said bowl having a portion thereof formed as a well communicating with the intake of the trapway, the faces of the interior of the bowl above its stated well portion being substantially smooth and of general conical contour solely increasing in effective radius upwardly without increase of the rate of increase of the radius, to thereby avoid re-entrant wall formation, means forming a jet opening communicating with the bowl below the normal fluid level of the trap sealing fluid for imparting vortical movement to substantially the whole of the fluid contained in the bowl, channel means having an outlet communicating with and directed upwardly of and in substantially parallel relation to the direction of flow through the trapway, passage means connecting said channel means with the vortex jet opening, and common means for supplying an effluent to said jet forming means and to said channel means, whereby the contents of the bowl is discharged without rise of the mean level of the fluid in the bowl.

3. A defecator comprising in combination a bowl having a portion thereof formed as the unobstructed upflow leg of a trapway, said bowl having a portion thereof formed as a well communicating with the intake of the trapway, the faces of the interior of the bowl above its stated well portion being substantially smooth and of general conical contour solely increasing in effective radius upwardly without increase of the rate of increase of the radius, to thereby avoid re-entrant wall formation, means forming a jet opening communicating with the bowl below the normal fluid level of the trap sealing fluid for imparting vortical movement to substantially the whole of the fluid contained in the bowl, channel means having an outlet communicating with and directed upwardly of and in substantially parallel relation to the direction of flow through the trapway, the jet opening and the outlet of the channel means being disposed below the normal level of the flowable mass contained within the well, and means for supplying an effluent to said jet forming means and to said channel means, whereby the contents of the bowl is discharged without rise of the mean level of the fluid in the bowl.

4. A defecator comprising in combination a bowl having a portion thereof formed as the unobstructed upflow leg of a trapway, said bowl having a portion thereof formed as a well communicating with the intake of the trapway, the faces of the interior of the bowl above its stated well portion being substantially smooth and of general conical contour solely increasing in effective radius upwardly without increase of the rate of increase of the radius, to thereby avoid re-entrant wall formation, means forming a jet opening communicating with the bowl below the normal fluid level of the trap sealing fluid for imparting vortical movement to substantially the whole of the fluid contained in the bowl, channel means having an outlet communicating with and directed upwardly of and in substantially parallel relation to the direction of flow through the trapway, passage means connecting said channel means with the vortex jet opening, the jet opening and the outlet of the channel means being

disposed below the normal level of the flowable mass contained within the well, and common means for supplying an effluent to said jet forming means and to said channel means, whereby the contents of the bowl is discharged without rise of the mean level of the fluid in the bowl.

5. A defecator comprising in combination a bowl having a portion thereof formed as the unobstructed upflow leg of a trapway, said bowl having a portion thereof formed as a well communicating with the intake of the trapway, the faces of the interior of the bowl above its stated well portion being substantially smooth and of general conical contour solely increasing in effective radius upwardly without increase of the rate of increase of the radius, to thereby avoid re-entrant wall formation, means forming a jet opening communicating with the bowl below the normal fluid level of the trap sealing fluid for imparting vortical movement to substantially the whole of the fluid contained in the bowl, channel means having an outlet communicating with and directed upwardly of and in substantially parallel relation to the direction of flow through the trapway, passage means extending adjacent the upper rim of the bowl and provided with openings arranged to discharge effluent in vortex relation with the flowable mass contained in the well, and means for supplying effluent to said jet forming means to said channel means and to said rim passage means, whereby the contents of the bowl is discharged without rise of the mean level of the fluid in the bowl.

6. A defecator comprising in combination a bowl having a portion thereof formed as the unobstructed upflow leg of a trapway, said bowl having a portion thereof formed as a well communicating with the intake of the trapway, the faces of the interior of the bowl above its stated well portion being substantially smooth and of general conical contour solely increasing in effective radius upwardly without increase of the rate of increase of the radius, to thereby avoid re-entrant wall formation, means forming a jet opening communicating with the bowl below the normal fluid level of the trap sealing fluid for imparting vortical movement to substantially the whole of the fluid contained in the bowl, channel means having an outlet communicating with and directed upwardly of and in substantially parallel relation to the direction of flow through the trapway, passage means extending adjacent the upper rim of the bowl and provided with openings arranged to discharge effluent in vortex relation with the flowable mass contained in the well, passage means connecting said channel means with the vortex jet opening, and common means for supplying effluent to said jet forming means to said channel means and to said rim passage means, whereby the contents of the bowl is discharged without rise of the mean level of the fluid in the bowl.

7. A defecator comprising in combination a bowl having a portion thereof formed as the unobstructed upflow leg of a trapway, said bowl having a portion thereof formed as a well communicating with the intake of the trapway, the faces of the interior of the bowl above its stated well portion being substantially smooth and of general conical contour solely increasing in effective radius upwardly without increase of the rate of increase of the radius, to thereby avoid re-entrant wall formation, means forming a jet opening communicating with the bowl below the normal fluid level of the trap sealing fluid for

imparting vortical movement to substantially the whole of the fluid contained in the bowl, channel means having an outlet communicating with and directed upwardly of and in substantially parallel relation to the direction of flow through the trapway, passage means extending adjacent the upper rim of the bowl and provided with openings arranged to discharge effluent in vortex relation with the flowable mass contained in the well, the jet opening and the outlet of the channel means being disposed below the normal level of the flowable mass contained within the well, and means for supplying effluent to said jet forming means and to said channel means and to said rim passage means, whereby the contents of the bowl is discharged without rise of the mean level of the fluid in the bowl.

8. A defecator comprising in combination a bowl having a portion thereof formed as the unobstructed upflow leg of a trapway, said bowl having a portion thereof formed as a well communicating with the intake of the trapway, the faces of the interior of the bowl above its stated well portion being substantially smooth and of general conical contour solely increasing in effective radius upwardly without increase of the rate of increase of the radius, to thereby avoid re-entrant wall formation, means forming a jet opening communicating with the bowl below the normal fluid level of the trap sealing fluid for imparting vortical movement to substantially the whole of the fluid contained in the bowl, channel means having an outlet communicating with and directed upwardly of and in substantially parallel relation to the direction of flow through the trapway, passage means extending adjacent the upper rim of the bowl and provided with openings arranged to discharge effluent in vortex relation with the flowable mass contained in the well, passage means connecting said channel means with the vortex jet opening, the jet opening and the outlet of the channel means being disposed below the normal level of the flowable mass contained within the well, and common means for supplying effluent to said jet forming means and to said channel means and to said rim passage means, whereby the contents of the bowl is discharged without rise of the mean level of the fluid in the bowl.

9. A defecator comprising in combination a bowl having a portion thereof formed as the unobstructed upflow leg of a trapway, said bowl having a portion thereof formed as a well communicating with the intake of the trapway, the faces of the interior of the bowl above its stated well portion being substantially smooth and of general conical contour solely increasing in effective radius upwardly without increase of the rate of increase of the radius, to thereby avoid re-entrant wall formation, means forming a jet opening communicating with the bowl below the normal fluid level of the trap sealing fluid for imparting vertical movement to substantially the whole of the fluid contained in the bowl, channel means having an outlet communicating with and directed upwardly of and in substantially parallel relation to the direction of flow through the trapway, means for supplying an effluent to said jet forming means and to said channel means, whereby the contents of the bowl is discharged without rise of the mean level of the fluid of the bowl, and means for receiving the discharge of the bowl including downwardly directed passage means connected to the outlet of the trapway, the downwardly directed passage

means forming with the trapway siphonic means for the discharge of the bowl.

10. A defecator comprising in combination a bowl having a portion thereof formed as the unobstructed upflow leg of a trapway, said bowl having a portion thereof formed as a well communicating with the intake of the trapway, the faces of the interior of the bowl above its stated well portion being substantially smooth and of general conical contour solely increasing in effective radius upwardly without increase of the rate of increase of the radius, to thereby avoid re-entrant wall formation, means forming a jet opening communicating with the bowl below the normal fluid level of the trap sealing fluid for imparting vortical movement to substantially the whole of the fluid contained in the bowl, channel means having an outlet communicating with and directed upwardly of and in substantially parallel relation to the direction of flow through the trapway, passage means connecting said channel means with the vortex jet opening, common means for supplying an effluent to said jet forming means and to said channel means, whereby the contents of the bowl is discharged without rise of the mean level of the fluid in the bowl and means for receiving the discharge of the bowl including downwardly directed passage means connected to the outlet of the trapway, the downwardly directed passage means forming with the trapway siphonic means for the discharge of the bowl.

11. A defecator comprising in combination a bowl having a portion thereof formed as the unobstructed upflow leg of a trapway, said bowl having a portion thereof formed as a well communicating with the intake of the trapway, the faces of the interior of the bowl above its stated well portion being substantially smooth and of general conical contour solely increasing in effective radius upwardly without increase of the rate of increase of the radius, to thereby avoid re-entrant wall formation, means forming a jet opening communicating with the bowl below the normal fluid level of the trap sealing fluid for imparting vortical movement to substantially the whole of the fluid contained in the bowl, channel means having an outlet communicating with and directed upwardly of and in substantially parallel relation to the direction of flow through the trapway, passage means extending adjacent the upper rim of the bowl and provided with openings arranged to discharge effluent in vortex relation with the flowable mass contained in the well, means for supplying effluent to said jet forming means and said channel means and said rim passage means, whereby the contents of the bowl is discharged without rise of the mean level of the fluid in the bowl, and means for receiving the discharge of the bowl including downwardly directed passage means connected to the outlet of the trapway, the downwardly directed passage means forming with the trapway siphonic means for the discharge of the bowl.

12. A defecator comprising in combination a bowl having a portion thereof formed as the unobstructed upflow leg of a trapway, said bowl having a portion thereof formed as a well communicating with the intake of the trapway, the faces of the interior of the bowl above its stated well portion being substantially smooth and of general conical contour solely increasing in effective radius upwardly without increase of the rate of increase of the radius, to thereby avoid re-entrant wall formation, means forming a jet opening communicating with the bowl below the

normal fluid level of the trap sealing fluid for imparting vortical movement to substantially the whole of the fluid contained in the bowl, channel means having an outlet communicating with and directed upwardly of and in substantially parallel relation to the direction of flow through the trapway, passage means connecting said channel means with the vortex jet opening, the jet opening and the outlet of the channel means being disposed below the normal level of the flowable mass contained within the well, common means for supplying an effluent to said jet forming means and to said channel means, whereby the contents of the bowl is discharged without rise of the mean level of the fluid in the bowl and means for receiving the discharge of the bowl including downwardly directed passage means connected to the outlet of the trapway, the downwardly directed passage means forming with the trapway siphonic means for the discharge of the bowl.

13. A defecator comprising in combination a bowl having a portion thereof formed as the unobstructed upflow leg of a trapway, said bowl having a portion thereof formed as a well communicating with the intake of the trapway, the faces of the interior of the bowl above its stated well portion being substantially smooth and of general conical contour solely increasing in effective radius upwardly without increase of the rate of increase of the radius, to thereby avoid re-entrant wall formation, means forming a jet opening communicating with the bowl below the normal fluid level of the trap sealing fluid for imparting vortical movement to substantially the whole of the fluid contained in the bowl, channel means having an outlet communicating with and directed upwardly of and in substantially parallel relation to the direction of flow through the trapway, passage means extending adjacent the upper rim of the bowl and provided with openings arranged to discharge effluent in vortex relation with the flowable mass contained in the well, means for supplying effluent to said jet forming means and said channel means and said rim passage means, whereby the contents of the bowl is discharged without rise of the mean level of the fluid in the bowl, and means for receiving the discharge of the bowl including downwardly directed passage means connected to the outlet of the trapway, the downwardly directed passage means forming with the trapway siphonic means for the discharge of the bowl.

14. A defecator comprising in combination a bowl having a portion thereof formed as the unobstructed upflow leg of a trapway, said bowl having a portion thereof formed as a well communicating with the intake of the trapway, the faces of the interior of the bowl above its stated well portion being substantially smooth and of general conical contour solely increasing in effective radius upwardly without increase of the rate of increase of the radius, to thereby avoid re-entrant wall formation, means forming a jet opening communicating with the bowl below the normal fluid level of the trap sealing fluid for imparting vortical movement to substantially the whole of the fluid contained in the bowl, channel means having an outlet communicating with and directed upwardly of and in substantially parallel relation to the direction of flow through the trapway, passage means extending adjacent the upper rim of the bowl and provided with openings arranged to discharge effluent in vortex relation with the flowable mass contained in the

well, passage means connecting said channel means with the vortex jet opening, common means for supplying effluent to said jet forming means and to said channel means and to said 5 rim passage means, whereby the contents of the bowl is discharged without rise of the mean level of the fluid in the bowl and means for receiving the discharge of the bowl including downwardly directed passage means connected to the outlet 10 of the trapway, the downwardly directed passage means forming with the trapway siphonic means for the discharge of the bowl.

15. A defecator comprising in combination a bowl having a portion thereof formed as the un- 15 obstructed upflow leg of a trapway, said bowl having a portion thereof formed as a well communicating with the intake of the trapway, the faces of the interior of the bowl above its stated 20 well portion being substantially smooth and of general conical contour solely increasing in effective radius upwardly without increase of the rate of increase of the radius, to thereby avoid re-entrant wall formation, means forming a jet 25 opening communicating with the bowl below the normal fluid level of the trap sealing fluid for imparting vortical movement to substantially the 30 whole of the fluid contained in the bowl, channel means having an outlet communicating with and directed upwardly of and in substantially parallel relation to the direction of flow through the trapway, passage means extending adjacent the upper rim of the bowl and provided with open- 35 ings arranged to discharge effluent in vortex relation with the flowable mass contained in the well, the jet opening and the outlet of the channel means being disposed below the normal level of the flowable 40 mass contained within the well, common means for supplying effluent to said jet forming means and to said channel means and to said rim passage means, whereby the contents of the bowl is discharged without rise of the mean level of the fluid in the bowl and means for receiving the discharge of the bowl including

downwardly directed passage means connected to the outlet of the trapway, the downwardly directed passage means forming with the trapway siphonic means for the discharge of the bowl.

16. A defecator comprising in combination a 5 bowl having a portion thereof formed as the un- obstructed upflow leg of a trapway, said bowl having a portion thereof formed as a well communicating with the intake of the trapway, the faces of the interior of the bowl above its stated 10 well portion being substantially smooth and of general conical contour solely increasing in effective radius upwardly without increase of the rate of increase of the radius, to thereby avoid re-entrant wall formation, means forming a jet 15 opening communicating with the bowl below the normal fluid level of the trap sealing fluid for imparting vortical movement to substantially the whole of the fluid contained in the bowl, channel means having an outlet communicating with and 20 directed upwardly of and in substantially parallel relation to the direction of flow through the trapway, passage means extending adjacent the upper rim of the bowl and provided with open- 25 ings arranged to discharge effluent in vortex relation with the flowable mass contained in the well, the jet opening and the outlet of the channel means being disposed below the normal level of the flowable 30 mass contained within the well, common means for supplying effluent to said jet forming means and to said channel means and to said rim passage means, whereby the contents of the bowl is disposed below the normal level of the flowable 35 mass contained within the well, common means for supplying effluent to said jet forming means and to said channel means and to said rim passage means, whereby the contents of the bowl is discharged without rise of the mean level of the fluid of the bowl, and means for receiving the discharge of the bowl including downwardly directed passage means connected to the outlet of the trapway, the downwardly directed passage means forming with the trapway siphonic means 40 for the discharge of the bowl.

WILLIAM C. GROENIGER.
